UNITED STATES PATENT OFFICE.

PETER ARNDT, OF LOS ANGELES, CALIFORNIA.

FLYING MACHINE.

Application filed December 5, 1927. Serial No. 237,877.

This invention relates to flying machines having large sustaining surfaces extending from the front to the rear.

One of the objects of this invention is to make such large sustaining surfaces or planes terminate close to the propeller in the front end and close to the tail end in the rear of a flying machine.

Another object is to provide large laterally extending wings above the longitudinally disposed sustaining surfaces.

Another object is to provide structures between the longitudinally and laterally disposed planes such as fuselage, cabins, and gondolas.

Another object is to form longitudinal air channels along the underside of the longitudinally disposed planes.

Other objects will appear from the following description and appended claims as well as from the accompanying drawings, in which—

Fig. 1 is a top plan view of a flying machine having a centrally disposed fuselage, a longitudinally disposed sustaining plane and laterally disposed planes illustrating a design for a smaller sized flying machine according to this invention.

Fig. 2 is a side elevation of the flying machine of Fig. 1.

Fig. 3 is a front elevation of the flying machine of Figs. 1 and 2.

Fig. 4 is a front elevation embodying principles of this invention designed for a larger sized flying machine.

Fig. 5 is a front elevation embodying principles of this invention designed for a special large flying machine.

Fig. 6 is a side elevation of a flying machine of the type illustrated in Fig. 4, showing the central fuselage or body from the foremost point or portion of this flying machine with the longitudinal plane extending from this foremost central position to the tail end of the flying machine, and with the upper structures in form of fuselages or cabins for the crew or passengers mounted above the longitudinally disposed plane by which the laterally projecting upper planes are supported above the longitudinal plane.

Fig. 7 is a top plan view of a flying machine of the type illustrated in Figs. 4 and 6, showing the longitudinally disposed plane of comparatively great width from a point near the front end of the flying machine to a point near the rear terminations of the

rear upper structures and from this point slanting towards the tail end of the flying machine.

Fig. 8 is a side elevation of a flying machine of the type illustrated in Fig. 5, being of a similar construction and having the longitudinal plane and upper structures as well as the lateral planes arranged similarly as the form illustrated in Figs. 4, 6, and 7, to which floats have been added below the longitudinal plane and the centrally disposed body.

Fig. 9 is a top plan view of the flying machine illustrated in Figs. 5 and 8, indicating the positions of the several propellers in front of the forward transversely disposed upper plane and in front of the rearward upper transversely disposed plane.

As illustrated in the drawing in Figs. 1, 7, 9 and 9, a comparatively large sustaining surface is provided to extend from the front end of the fuselage to the rear end.

For smaller sized flying machines this large sustaining surface is made of a form of 80 a longitudinally disposed plane indicated in Figs. 1, 2, and 3 at 10. This longitudinally disposed plane is preferably channeled in the underside as distinctly shown in Fig. 3. The whole longitudinal plane 10 is formed in the 85 underside beginning in the front end with a comparatively large arched portion as indicated at 11, and terminating at the rear end in a smaller arched portion as indicated at 12 in Fig. 3. The front edge 13 of this plane 90 is disposed as close as possible to the front end 14 of the fuselage 15, and the rear edge 16 of this plane terminates at or as close as possible near the rear end of the fuselage 15.

A laterally disposed plane 17 is mounted 95 above and near the front end of the fuselage. Elevators 18 are mounted movably near the rear end of the fuselage together with other steering surfaces indicated at 19. A tail skid 20 is provided on the underside of the fuselage and below the longitudinal plane 10. The fuselage and whole plane structure are supported by wheels 21 braced as indicated at 22. A propeller 23 is provided on the front end of the fuselage.

For larger flying machines the longitudinally disposed plane is preferably hollow or channeled more than once in the underside as clearly illustrated in Figs. 4 and 5. The centrally disposed bodies 24 and 25 serve 110 in larger flying machines for storing purposes and eventually as quarters for the

crew, while cabins and other quarters for passengers are provided above the longitudinally disposed large plane as indicated at 26 in Fig. 4 and at 27 in Fig. 5. The body 24 in the form illustrated in Fig. 4 together with the edges 28 of the longitudinal plane 10_a serve to form longitudinal channels on the opposite sides of the centrally disposed body or main fuselage.

10. In the special large design illustrated in Fig. 5, however, the longitudinal plane is distinctly formed with longitudinal channels in the underside as clearly illustrated in Fig. 5, indicated at 29.
15. The transversely disposed wings 30 and 31 in the flying machine illustrated in Figs. 4, 6 and 7 are supported above the longitudinally disposed plane 10_a by the upper structures 26_a and 26_b. These upper structures in form of fuselages contain cabins for passengers and other purposes. The forward structures 26_a are constructed to also hold a motor in their front ends 32 to actuate the propellers 33, while the rear structures 26_b have no such provisions for any motors or propellers. On the rear wings 31 are for this reason extra provisions to support motors at the points indicated at 34 to actuate the propellers 35.
30. The lower fuselage or main body 24 carries a motor to actuate the propeller indicated at 36.

As illustrated in Fig. 7, the longitudinally disposed plane 10_a is formed to support the front as well as the rear upper structures and from the rear upper structure rearwardly slants towards the tail end of the flying machine as indicated at 37. The whole flying machine is supported by the running gear indicated at 38, braced to the structure at points about below the front and rear upper structures.

For extra large flying machines as illustrated in Figs. 5, 8, and 9, additional provisions are made as indicated at 40 to actuate propellers 41, so that these extra large machines are actuated by five propellers in the front and two propellers just on the front edge of the rear wings 42. This

large flying machine is provided with floats 50 43 under the front end of the machine and with another float 44 under the rear end of the machine. The floats and running gear 45 are braced to the whole flying machine structure at points about below the upper 55 structures 27_a and 27_b.

Having the longitudinal comparatively large sustaining surfaces and planes arranged below and extending to the sides of the upper structure provides possibilities 60 that in cases of necessity passengers may be transferred from cabins in one of the upper structures to cabins of any of the other upper structures provided in any flying machine of this type. Railings are, therefore, provided on top of the large longitudinal planes as indicated at 46 so that people may be guided while passing over the top of the large longitudinal plane.

Having thus described my invention, I 70 claim:

1. In a flying machine, a centrally disposed fuselage, a longitudinally disposed plane projecting to both sides of the fuselage from a point near the front end to a 75 point near the rear end of the fuselage, transversely disposed planes projecting beyond the outer lateral contours of and being spaced above the first-named plane, upper structures disposed between the longitudinally and laterally disposed planes, and protecting means between the upper structures by which a person may guide himself in passing from one upper structure to another while walking over the top of said longitudinally disposed plane.

2. In a flying machine, a longitudinally disposed plane and longitudinally channelled in its underside, transversely disposed planes spaced above the first plane, and a fuselage 90 disposed between the first and second-named planes connecting the planes and embodying cabins adapted to be reached from the top surface of the first-named longitudinally disposed plane.

In testimony that I claim the foregoing as my invention I have signed my name.

PETER ARNDT.
